ANTI-THUMB-SUCKING DEVICE

Filed Jan. 18, 1930

UNITED STATES PATENT OFFICE

JOHN H. DAVIS, OF SIOUX CITY, IOWA

ANTI-THUMB-SUCKING DEVICE

Application filed January 18, 1930. Serial No. 421,698.

My invention relates to anti-thumb sucking devices for infants and has for its object to provide a device of this character which is simple, durable and inexpensive in construction and which may be easily constructed of sheet metal or the like.

Another object is to provide a device of this class including means for securing the device to the hand of an infant in such a manner that the infant cannot release his thumb from the confinement of the device.

Another object is to provide a device which will be positive in its action, preventing the infant obtaining suction against any portion of the thumb.

A further object is to provide a device which, in addition to accomplishing all of the foregoing objects, will be perfectly safe and will not injure the mouth of the infant in any manner.

With these and other objects in view, my invention consists in the construction, arrangement and combination of the various parts of my device, whereby the objects contemplated are attained, as hereinafter more fully set forth, pointed out in my claim, and illustrated in the accompanying drawings, in which:

Fig. 1 is a view of the device installed on the hand of an infant, looking toward the palm of the hand.

Fig. 2 is a similar view looking toward the side of the hand.

Fig. 3 is a perspective view of the device and

Fig. 4 is a plan view of a blank from which the device is made.

The primary object of devices of this character is to prevent the infant obtaining suction against his thumb. The usual method is to provide a casing into which the thumb is inserted together with means for fastening the casing to the hand and perforating the casing in such a manner that the infant will obtain air if it sticks the casing and thumb in his mouth and applies suction thereto. Since the infant derives no satisfaction from the thumb sucking process if it obtains air or cannot produce suction against the thumb, the effectiveness of such devices lies in the effec-

tive providing of air under all circumstances or stated in another manner, the effective prevention of the obtaining of suction.

Among those devices which have been provided for this purpose, many of them are dangerous to the infant, owing to the nature of the protruding openwork embodied in them. One of the primary objects of the present invention has been therefore to provide a device which is safe but along with this object, it is desirable to provide a device which can be inexpensively made.

Probably the most difficult problem contended with in devices of this character is that of insuring that the device will remain on the thumb of the infant. An infant's thumb is very flexible, is inclined to be fat and soft rather than thin and bony and the ordinary infant with a normal amount of active impulse is very ingenious in working his thumb loose from the confinement of a device of this character.

By bending the tip of the thumb toward the palm of the hand, the infant can move the tip in a direction circumferential of a point located in the wrist. The wrist proves to be the only practical place for attachment of the securing means and thus the problem of securing of the device becomes rather complex. It will be remembered, of course, that it is desirable to provide attaching means which can be attached in a very simple manner.

My invention in this respect has solved the problem to such an extent that the attachment is made by the simple process of extending the cord around the wrist of the infant and securing the ends together in one spot. Turning now to the drawings, the device comprises a tube 10, adapted to receive substantially the full length of the thumb of an infant. The tube is perforated as at 11 so that air from within the tube may enter the mouth of an infant. A band 12 is provided extending from one side to the other of the tube and projecting away from the end thereof, said end being open as at 13. The object of the band 12 is to prevent the infant from closing the mouth of the tube with his tongue. It will be understood that

by closing the mouth of the tube with his tongue and simultaneously closing the first row of openings with his lips, that the infant might still obtain suction against his thumb 5 when the device is in place.

One side of the tube 10 is continued to form a projecting arm 14, curved so as to fit that portion of the hand which forms a continuation of the thumb. Openings 15 are 10 provided in the end corners of the arm 14 and a wrist cord 16 is passed through the openings so as to provide two projecting cord portions adapted to be extended around the wrist 17 of the infant and tied together.

15 An opening 18 is provided in the sleeve 10 near the end opposite the band 12 and diametrically opposed to the arm 14. A cord 19 is secured to the sleeve being threaded through the opening 18 and is provided with 20 a loop 20 which receives the wrist cord 16.

The arm 14 being secured to the wrist by the cord 16 prevents the infant from removing his thumb by bending the tip toward the palm. The cord 19 prevents the infant from 25 removing the thumb in the opposite direction. In this connection, I have discovered that an infant can remove its thumb by exerting pressure against the tube 10, tending to pull the tube toward the tip of the thumb 30 and away from the forefinger of the hand, the thumb flexing inwardly until it will finally pass the inner extremity of the tube 10.

35 The cord 19 prevents removal of the thumb in this way, holding the tube so as to limit the possible movement of the tube toward the tip of the thumb.

Both the arm 14 and cord 19 cooperate to retain the device on the infant's thumb. 40 Without the arm 14, the cord 19 would be of little value and without the cord 19, the arm 14 would not be efficient in retaining the device on the infant's thumb.

The blank for making the device is shown 45 in Fig. 4, the band 12 being formed integrally at one end with the portion which forms the tube 10 and at its other end being welded to the tube 10 during the formation of the device. The edges 21 of the body of the 50 blank are butt welded together or soldered to form the cylindrical tube portion 10.

Some changes may be made in the construction and arrangement of the parts of my invention without departing from the 55 real spirit and purpose of my invention, and it is my intention to cover by my claim any modified forms of structure or use of mechanical equivalents, which may be reasonably included within their scope.

60 I claim as my invention:

An anti-thumb sucking device for infants comprising a cylindrical portion adapted to receive the infant's thumb, a projection aligned with one side of the cylindrical portion, adapted to lie against and to fit the

contour of the back of the thumb portion of the infant's hand, said projection being relatively wide, solid, and flat at its end, a flexible element secured to the end of the projection at two points positioned respectively near the opposite edges thereof and adapted to encircle the wrist of the infant, and a tie element secured to the cylindrical portion substantially diametrically opposite the projection, adapted to extend from the base of the thumb on the palm side thereof and to be secured to the flexible element on the palm side of the hand.

Signed this 11th day of January, 1930, in the county of Woodbury and State of Iowa. 80
